UNITED STATES PATENT OFFICE.

ARIOUSE Z. HALL AND WILLIAM A. HUGHES, OF NASHVILLE, TENNESSEE, ASSIGNEES
TO SCOTT & WILLIAMS, INC., OF NEW YORK, N. Y., A CORPORATION OF MASSACHU-
SETTS.

STOP MOTION FOR CIRCULAR-KNITTING MACHINES.

Application filed November 5, 1921. Serial No. 513,052.

To all whom it may concern:

Be it known that we, ARIOUSE Z. HALL and WILLIAM A. HUGHES, citizens of the United States, residing at Nashville, in the county of Davidson and in the State of Tennessee, have invented a new and useful Improvement in Stop Motions for Circular-Knitting Machines, of which the following is a specification.

10 Our invention relates to a device for circular knitting machines in which a single member acts both as welt-presser and detector for defective needles. It is an improvement on the devices shown in Robert W. Scott's Patents Nos. 1,270,064 dated June 18, 1918, and 1,282,958 dated October 29, 1918.

This executive member, which we shall call the presser-detector, is generally pivoted on the standard supporting the latch ring.

20 Its field of operation lies just above the cap ring, sinkers and cylinder needles at the knitting point, and between the needle cylinder and dial plate. The normal operation of the machine as well as the actuation

25 of the stop motion requires complete or partial withdrawal of the presser-detector from its usual forward position between the needle cylinder and dial plate. The presser-detectors have heretofore been arranged to 30 swing on a fixed center. Great delicacy of adjustment has been required to properly isolate the various functions of the presser-detector. This delicacy is hard to maintain in practical operation.

35 Our invention does away with the necessity for delicacy of adjustment and gives a positive and quick tripping of the stop motion. It also permits greater length-wise movement of the presser for yarn-guiding purposes. It eliminates all interference between the functions of pressing the welt and detecting trouble in the needle cylinder. We accomplish this by means of a novel sliding pin and slot connection between the 45 presser-detector, the machine and its control devices.

In the accompanying drawings—

Fig. 1 is a plan of sufficient of a circular knitting machine embodying our invention 50 to show its operation;

Fig. 2 shows our presser-detector and its immediate connections;

Fig. 3 is a vertical section through sufficient of the head of a machine to further illustrate the position of our presser-detector.

Fig. 4 is a detail view including arm p^5 . The presser-detector is shown in its normal operative or forward position in Fig. 1. Instead of fastening it to standard 1 by a fixed pivot we give it a moving pivot by inserting screwstud 2 through slot 3 of the presser-detector 4 into the standard 1. By means of spring 5 and pin 6 the presser-detector 4 is kept pointed toward the center of the needle cylinder unless hit by a needle. 60 The presser-detector 4 is connected by wire 8 to the stop motion 9. This wire 8 carries an adjustable collar 10 bearing against lever 11 when the presser-detector is forward or completely withdrawn. To make 70 the collar 10 bear against lever 11 when the presser detector is in these positions, the connection 12 between the wire 8 and presser-detector 4 should be so placed that the wire and presser-detector are at right angles when 75 the latter is half withdrawn.

Any suitable means acting lengthwise on the presser-detector may be used to press the welt or guide splicing yarns under the dial. We have shown in Fig. 1 the well-known 80 means described in Scott's Patent 1,282,958. The wire link p^3 is hooked to the presser-detector at 12 and passed through a hole in the vertical arm p^5 of a rocker p^6 swinging on stud 472 in a fixed part of the machine. 85 A compression spring p^4 surrounds link p^3 and taking against a stop thereon provides means for holding the presser-detector forward under spring pressure at the desired parts of the knitting. 90

As shown in Fig. 2 the body of the presser-detector is longitudinal in shape and has a slot 3 in it.

Fig. 3 shows the relation of point 7 to the dial plate 13 and the needles 14. 95

The operation of our presser-detector is as follows. When doing circular knitting the compression spring p^4 holds the presser-detector forward. The presser-detector can then press a welt, guide yarns under the dial plate as described in Scott's Patents Nos. 1,256,062 and 1,282,958 or detect misplaced needles. When a yarn change is due the cam cylinder will withdraw the arm p^5 . This will retract link p^3 and pull back the 105 presser-detector. By reason of screw stud 2, spring 5 and pin 6 the presser-detector moves in a straight line when actuated by link p^3 . Since wire 8 is at right angles to the presser-detector when the latter is midway in its 110

linear movement, and the collar 10 just touches lever 11 when the presser detector is at the extremes of its linear motion, it follows that the stop motion 9 is unaffected by any movement of the presser-detector caused by link p^3 .

At all times that the presser-detector has its point 7 over the needle circle it is ready to detect needles which are not depressed by 10 the knitting cam. When hit by such a needle the presser-detector instantly swings away from pin 6 in a pivoted movement and trips the stop motion 9. Since the collar 10 is touching the lever 11 before the defective 15 needle hits the presser-detector, it follows that the stop motion is tripped at the instant of impact.

It is understood that wire 8 may be connected to an alarm means, rather than a 20 stop motion, if that is preferred.

We claim:

1. In a circular knitting machine, a member functioning with a rotary motion as a detector for a stop motion, and with a 25 straight-line motion as a welt presser.

2. In a circular knitting machine, a member functioning with a rotary motion as a detector for a stop motion and with a straight-line motion in a direction radial to the needle circle as a welt presser.

3. In a knitting machine, a welt pressing and stop motion device comprising a stop motion, an executive member whose turning movement actuates said stop motion, and means imparting straight-line movement to 35 said member for pressing the welt.

4. In a knitting machine, a welt pressing and stop motion device comprising a presser-detector fastened on a sliding pivot, a pin, a spring holding said presser-detector 40 against said pin in opposition to a pivoting movement, a stop-motion actuated by said pivoting movement and means imparting straight-line movement to said presser-detector for pressing the welt.

In testimony whereof we have signed our names to this specification.

ARIOUSE Z. HALL.
WILLIAM A. HUGHES.
